A. E. DOMAN,
BLANK FOR MANUFACTURING COMMUTATOR BARS,
APPLICATION FILED JULY 9, 1917.

Patented Oct. 22, 1918.

FIG. 1.

FIG. 2.

FIG. 4.

FIG. 3.

Albert E. Doman ^{INVENTOR}
By Kosarad P. Seulon
^{ATTORNEY}

UNITED STATES PATENT OFFICE.

ALBERT E. DOMAN, OF ELBRIDGE, NEW YORK, ASSIGNOR, BY MESNE ASSIGNMENTS, TO DYNETO ELECTRIC CORPORATION, OF SYRACUSE, NEW YORK, A CORPORATION OF NEW YORK.

BLANK FOR MANUFACTURING COMMUTATOR-BARS.

1,282,052.

Specification of Letters Patent. Patented Oct. 22, 1918.

Original application filed December 26, 1916, Serial No. 138,971. Divided and this application filed July 9, 1917. Serial No. 179,495.

To all whom it may concern:

Be it known that I, ALBERT E. DOMAN, a citizen of the United States of America, and resident of Elbridge, in the county of Onondaga, in the State of New York, have invented new and useful Improvements in Blanks for Manufacturing Commutator-Bars, of which the following, taken in connection with the accompanying drawings, is 10 a full, clear, and exact description.

This invention relates to certain improvements in the manufacture of commutators and parts thereof and in the blank from which the bars or segments thereof are 15 made and is a division of my copending application, Ser. No. 138,971 filed December 26, 1916.

The primary object of the invention is to 20 reduce the expense of raw materials, as copper, and the cost of manufacture by forming the raw materials preferably in long, cold drawn strips tapered laterally from a central portion or formed with a double bevel so that the bars, with suitable integral tangs, 25 may be punched from the strips with but slight waste of material, the angle or bevel of the strip being of such degree as to correspond with a required angle when a predetermined number of bars or segments are to 30 be nested together to form a complete cylinder.

Other objects and advantages will appear 35 from the following description taken in connection with the accompanying drawings, in which—

Figure 1 is a view of the blank of this invention from which the commutator bars or segments may be punched.

Fig. 2 is a top plan view of the blank, the 40 shape of the bars and the method of punching being indicated.

Fig. 3 is a view of a complete bar or segment.

Fig. 4 is a cross section of a commutator as 45 constructed from such segments.

The invention, as shown, comprises the blank —1— which may preferably be a relatively long, cold drawn strip of suitable material, as copper, having a central substantially plane horizontal portion —2— with side portions —3— and —4— tapered or beveled in opposite directions therefrom.

Both sides of the blank are symmetrical and of the same conformation.

The side portions —3— and —4— are 55 disposed at the same angle relatively to the portion —1— and are of equal width, the angle of disposition of the outwardly converging portion —3— or the outwardly converging portion —4— being of such a degree as is required in the manufacture of a complete cylinder from a predetermined number of similarly shaped nested bars or segments. With a commutator constructed of thirty-three bars or segments, as here 60 illustrated, the angle of disposition of the outwardly converging side portions —4— or the outwardly converging side portions —3— is approximately 10°, 54', 32". The angle of disposition of each beveled portion 70 —4— or each beveled portion —3— and the central portion —2— being approximately one-half the angle last described. The angular disposition will, of course, vary in accordance with the number of segments to be 75 used in forming a complete cylinder.

The strip —1— is of a width equal to the complete width of the commutator bar —5— including the tang —6— for electrical connections and is twice the width of the body 80 —7— of the commutator bar adapted to form the cylindrical portion of the commutator.

From the strip —1— commutator bars —5— can be punched or cut with a minimum waste of material and with a minimum cost of production in the manner shown in Fig. 2. The bar is punched along lines 8, 9 and 10, the line 8 extending from one side of the bar to the central portion of the bar, said line being spaced from the adjacent end of the strip —1— a distance equal to the desired width of tang —6—. The line —9— extends from the inner termination of line —8— longitudinally and centrally of the 95 strip —1— a distance equal to the desired width of the body of the commutator bar adapted to form the cylindrical portion of the commutator. The line —10— extends from the termination of line —9— to the edge of 100 the bar opposite that at which the line —8— terminates. Preferably portions —13— and —14— are cut from the edge of the bar to form, in connection with body —7—, an in-

tegral wedge-shaped member —11— adapted to receive suitable, usual and well known means, as ring members, for holding the segments in nested position in the completed 5 commutator. These portions —13— and —14— which are cut out to form the wedge-shaped member —11— are the only waste material in constructing the commutator bars.

10 In order to form the second commutator bar, the strip is punched along line —12— and the portions —13— and —14— are preferably punched out to form the wedge-shaped member —11—. The line —12— is 15 spaced from the line —10— a distance equal to the desired width of tang —6—. By this method of cutting or punching, two complete commutator bars are cut from a strip of material equal in width to the radial 20 length of a commutator bar and equal in length to the complete width of a commutator bar plus the width of one tang.

25 The bars, as shown, may be mounted upon a suitable sleeve or core —15— and may be held in assembled position upon the sleeve in any suitable and usual manner.

30 Although I have shown and described one particular construction and exact method as constituting a preferred embodiment of this 35 invention, it will be apparent that changes and alterations may be made in the exact form of the commutator bar and the exact method of punching the same without departing from the spirit of this invention as set forth in the appended claims.

What I claim is:

1. A blank for manufacturing commutator bars consisting of a relatively thin wide strip of suitable material tapered laterally 40 from an intermediate portion toward its opposite edges, the opposite flat surfaces of said tapered portions forming substantially

equal angles with the central plane connecting opposite edges of the blank.

2. A blank for manufacturing commutator bars consisting of a relatively thin wide strip of suitable material, the width of the same being substantially equal to the maximum radial width of the commutator bar when assembled, said bar tapered from an 50 intermediate portion toward opposite edges, the angular disposition of the outwardly converging walls of said side portions corresponding to the required angle for producing a complete cylinder from a predetermined number of similar substantially radially arranged segments. 55

3. A blank for manufacturing commutator bars consisting of a relatively thin wide strip of suitable material having a central plane portion with opposite sides substantially parallel and opposite side portions having their opposite walls converging outwardly, the opposite walls of said side portions forming substantially equal angles with the 60 central plane connecting opposite edges of the blank. 65

4. A blank for manufacturing commutator bars, consisting of an elongated strip of suitable material having a central plane portion with opposite sides substantially parallel and opposite side portions having their opposite walls converging outwardly, the angle of disposition of the outwardly converging walls of each side portion corresponding to the required angle for producing a complete cylinder from a predetermined number of similar nested segments. 75

In witness whereof I have hereunto set my hand this 27th day of June, 1917.

ALBERT E. DOMAN.
